UNITED STATES PATENT OFFICE

CLIFFORD J. COWMAN, OF MALLARD, IOWA

HUMIDIFIER

Application filed October 2, 1930. Serial No. 486,039.

The principal object of this invention is to provide an efficient humidifier for all enclosed spaces that require the atmosphere therein to possess a relatively great moisture content, such as cigar cases, incubators, and the like.

A further object of my invention is to provide a humidifier that successfully supplies moisture uniformly to all parts of the case or housing in which it functions.

A still further object of this invention is to provide a humidifier that is easily installed in a case and when once installed provides a support for objects such as cigar boxes.

15 A still further object of my invention is to provide a humidifier that requires a minimum number of water replenishings over a certain period of time.

20 A still further object of my invention is to provide a humidifier that is economical in manufacture and durable in use.

These and other objects will be apparent to those skilled in the art.

25 My invention consists in the construction, arrangement and combination of the various parts of the device, whereby the objects contemplated are attained as hereinafter more fully set forth, pointed out in my claims and illustrated in the accompanying drawings, in which:

30 Fig. 1 is a top plan view of my complete humidifier with sections cut away to illustrate its construction.

Fig. 2 is a cross sectional view of the device taken on line 2—2 of Fig. 1, and more fully shows its interior construction.

35 Fig. 3 is a side view of a section of the trough.

40 Fig. 4 is a top view of a portion of the perforated metal lid of the invention.

The familiar humidifier now on the market uses a container for holding the water and a wick or wicks extending from the container. 45 Such humidifiers are objectionable as the loose wicks often become detached from the container, require constant attention and are more moist near the container than some distance away from the container, thereby providing uneven moistening of the atmosphere.

inside the case. I have overcome such objections as will hereinafter be appreciated.

I have used the numeral 10 to designate the frame of the device made of wood or other suitable material. Embraced by this frame 55 10 as shown in Fig. 2, is a slab 11 of absorbent material such as compressed fibrous pulp, sponge stone or the like. The numeral 12 represents a continuous wall resting on top of the member 11. This wall 12 should conform to the general outline of the frame 10 and have an outside diameter slightly less than the inside diameter of the frame 10, as shown in Fig. 1. This retaining wall 12 extends to a height approximately the height 60 of the frame 10 and should be so tightly attached to the member 11 that liquid will not pass between the bottom of the retaining wall 12 and the top surface of the slab 11. In the drawings I show nails 13 and cement which 65 is not numbered.

Loosely resting on the top of the slab 11 and inside the retaining wall 12 is a sheet wick 14 of asbestos or other suitable highly absorbent material. The numeral 15 designates a comparatively small elongated bottomless trough resting on and approximately in the center of the wick 14. This trough is held in place by being rigidly secured to the slab 11 by suitable means such as small 70 nails. The numeral 16 designates small outlet ports in the lower portion of each side of the trough 15. These ports 16 are adjacent the wick 14 and permit water from the trough 15 to rapidly pass and spread out over the 75 wick 14. The numeral 17 designates a porous sheet secured by suitable means to the top of the frame 10 and completely covering the same. It is recommended that this porous sheet be made of suitable non-rusting metal such as sheet aluminum or the like. The numeral 18 designates a plurality of supporting bars nailed on top of the porous member 17 and nailed rigidly to the frame or wall 12 and the trough 15.

The numeral 19 designates strengthening and filling bars secured on the underside of the slab 11. These bars are of such dimension as to extend down to a plane common to the bottom of the frame 10. The numeral 20

designates air ports in the lower portions of the frame 10 and bars 19 for permitting air to circulate to and reach the bottom of the slab 11.

- 5 The numeral 21 designates a water filling opening in the member 17 and directly above the trough 15.

To use my invention it is merely necessary to place the same inside the case or enclosure 10 desired to be kept at proper humidity and place water into the trough 15 through the opening 21.

This water in the trough 15 will engage the wick 14 at the bottom of the trough, and 15 will by capillary action conduct the water completely across and over the slab 11. This passing of the water from the trough 15 is also aided by the small outlet ports 16 in the two sides of the trough 15 which permits 20 the water in the trough to run out and over the wick 14. If sufficient water is placed in the trough 15 it will eventually completely 25 saturate the slab 11. As the wick 14 starts to dry by the evaporation of the water moisture in the same it will proceed to draw additional moisture from the moisture retaining slab 11, however, the slab 11 is comparatively thick and is capable of reservoiring a 30 great amount of water, the device will continue to properly function for a comparatively great length of time, thereby eliminating frequent fillings of the trough 15. By the slab 11 supporting the complete underside of 35 the wick 14, the total surface of the wick 14 will be evenly moist at all times from the slab 11, thereby uniformly moistening the air inside the enclosure having the humidifier.

By the construction of my humidifier as herein disclosed, it will be noted that there 40 are no parts to become detached one from the other either during use or shipping. By the retaining wall 12 being sealed to the slab 11 there is no danger of placing an excess amount of water in the device which would otherwise 45 pass through to the bottom of the frame 10 with a possibility of damaging other objects also inside the case.

The ports 20 allow air to circulate under the slab 11 which not only aids in humidifying 50 the air inside the case but prevents any molding or foul air to exist at the bottom of the invention. By the wick 14 covering the upper surface of the slab 11, the undesirable rapid drying of the slab 11 is eliminated.

55 The device occupies very little space inside an enclosure such as a cigar case and after being placed in the case, cigar boxes or the like, may be placed on the supporting bars 18.

If it is desired all of the parts that go to 60 make up my device except the slab 11 and wick 14 may be made of metal. Two or more wicks may be used instead of the single wick 14 and when this is done the top wick should not extend into the trough but should merely 65 rest on top of the lower wick. In Figure 2,

I have shown an extra wick on top of the wick 14 and which I have designated by the numeral 22.

Some changes may be made in the construction and arrangement of my improved humidifier without departing from the real spirit and purpose of my invention, and it is my intention to cover by my claims any modified forms of structure or use of mechanical equivalents which may be reasonably included within their scope.

I claim:

1. In a device of the class described, a frame, a thick sheet of pervious material secured in said frame, a comparatively thin wick member resting on said comparatively thick sheet of pervious material and a container designed to receive liquid and communicating with said comparatively thin sheet of material.

2. In a device of the class described, a slab of pervious material, a frame embracing said slab, a sheet wick of absorbent material resting on the top surface of said slab, a trough open at its bottom secured on top of said sheet of absorbent material, and a porous metallic sheet inclosing the top of said frame and secured to said frame and the top of said trough.

3. In a device of the class described, a slab of pervious material, a frame embracing said slab, a sheet wick of absorbent material resting on the top surface of said slab, a trough open at its bottom secured on top of said sheet of absorbent material, a porous metallic sheet inclosing the top of said frame, and supporting bars on top of said porous sheet secured to said frame and the top of said trough.

4. In a device of the class described, a slab of pervious material, a frame embracing said slab, a sheet wick of absorbent material resting on the top surface of said slab, a trough open at its bottom secured on top of said sheet of absorbent material, a porous metallic sheet inclosing the top of said frame having a filling opening above said trough, supporting bars on top of said porous sheet, and air passageways in the lower portions of said frame which permits air to circulate below 115 said slab.
